CONVERTIBLE VACUUM SWEEPER AND FLOOR POLISHER

Filed Oct. 25, 1926

2 Sheets-Sheet 2

UNITED STATES PATENT OFFICE.

ERNEST H. BLANCHARD, OF SCHENECTADY, AND DARWIN MOTT, OF GLENVILLE,
NEW YORK.

CONVERTIBLE VACUUM SWEEPER AND FLOOR POLISHER.

Application filed October 25, 1926. Serial No. 143,869.

Reference may be had to the accompanying drawings, and the reference characters marked thereon, which form a part of this specification. Similar characters refer to 5 similar parts in the several figures therein.

The principal object of the invention is to easily and quickly convert a vacuum sweeper into a floor polisher.

Other objects will appear in connection 10 with the following description.

Fig. 1 of the drawings is a bottom plan view of a machine adapted for use in accordance with our invention with the machine equiped for use as a surface polisher, 15 the handle and dust-bag being partly broken away.

Fig. 2 is a view partly in side elevation and partly in vertical section of the machine, as shown in Fig. 1.

20 Fig. 3 is a view in perspective of the plate for closing the inlet-port to the fan-chamber.

Fig. 4 is a longitudinal vertical section taken on the broken line 4—4 in Fig. 1, 25 through a broken-away portion of the machine.

Referring to the drawings wherein the invention is shown in preferred form, 1 is the body of the machine which is mounted upon 30 a pair of front wheels 2—2 and a pair of rear wheels, 3—3, which wheels are adapted to travel over a floor surface, 4, or the like.

Mounted upon the body, 1, is an electric motor, 5, the case only of which is shown, 35 which motor drives a fan-shaft, 6, rotatory upon a vertical axis.

Electric current for the electric motor, 5, is supplied through a cable, 7, in the usual manner.

40 Beneath the electric motor, 5, the body of the machine is formed or provided with a fan-chamber, 8, within which is rotatively mounted a fan, 9, fixed upon the fan-shaft, 6.

45 The fan-chamber, 8, is provided with a bottom inlet-port, 10, which is adapted to be connected as hereinafter described with a passageway or throat, 11, of a brush-chamber, 12, extending across the front end of the machine.

The passageway or throat, 11, extends through the body, 1, of the machine approximately to the inlet opening, 10, in the

bottom of the fan-chamber, and is adapted to be completed by means of a removable 55 cap, 12^a, (shown in dotted lines in Fig. 2) mounted upon the body, 1, by means of studs, on the front end of the cap which engage respective openings in the body, 1, of the machine, and a tongue, on the rear end 60 of the cap adapted to be underlyingly engaged by a slide, 15, mounted in a suitable slideway, 16, upon the body of the machine.

By moving the slide, 15, to one side of its position underlying the tongue, the cap 12^a 65 will be disengaged and can be downwardly tilted and its studs, withdrawn from their respective apertures in the body of the machine to release and permit the removal of the cap.

70 The fan-shaft, 6, extends downwardly through the inlet-port, 10, of the fan-chamber and has fixed upon its lower end a belt pulley, 17, connected by a belt, 18, extending through the throat or passageway, 11, with a brush, 19, rotatively mounted within the brush-chamber, 12, whereby the electric motor, 5, serves as a common means for driving both the fan and the brush, 19.

75 The brush, 19, may be a cylindrical brush 80 of any known kind,—a cylindrical brush including numerous bunches, 20, of bristles or brush fibre being shown.

For certain purposes of the present invention, it is desirable that the periphery 85 of the brush, 19, shall engage the floor surface, 4, and the peripheral portion of the brush may be made of any material adapted for the kind of treatment to which it is desired to apply any substance to the floor; any 90 other polishing or abrading material may be substituted for the bristle tufts, 20.

An outlet, 21, leads from the fan-chamber to a dust-bag, 22, shown partly broken away.

95 The machine is adapted to be propelled over the floor surface, 4, by means of a handle, 23, in the usual manner.

In carrying out our invention, we provide a closure for the inlet opening, 10, of the 100 fan-chamber in the form of a plate, 24, provided with an aperture, 25, adapted to closely receive the lower end, 6^a, of the fan-shaft and having on its forward end downwardly projecting arms, 26, formed with studs, 13^a, 105 adapted, when the cap, 12, is removed, to

engage the respective apertures in the body of the machine which are engaged by the studs, on the cap, 12^a, when the cap is locked in position on the machine.

5 The plate, 24, has a rearwardly projecting tongue, 27, adapted to be underlyingly engaged by the slide, 15, to secure said plate against the bottom of the fan-chamber in position to close the inlet-port thereto, as shown in Figs. 1 and 2.

10 In the type of machine shown, the closure-plate, 24, and the cap, 12^a, are adapted for alternate use, but for certain purposes of the invention any known form of removable closure, for the inlet-port of the fan-chamber may be employed.

15 The operation of the machine is as follows:

When it is desired to use the machine as 20 an ordinary vacuum cleaner or sweeper, the closure-plate, 24, is removed and in place thereof, the cap, 12^a, is mounted upon the body of the machine as indicated by dotted lines in Fig. 2, to complete the throat or 25 passageway, 11, from the brush-chamber, 12, to the inlet, 10, of the fan-chamber, 8.

The machine is then operated in the usual manner, the brush and fan being rotated by the electric motor, 5, and the dust or dirt is 30 agitated by the brush, 19, and drawn through the throat, 11, from the brush-chamber, 12, into the fan-chamber, and then is expelled through the outlet, 21, into the dust-bag, 22, in the usual manner.

35 The machine is used in the described manner with a brush, 19, of a suitable character for any treatment of the floor surface which involves the removal of dust, dirt or other matter not injurious to the dust-bag, 22, and not injurious to, or tending to clog, 40 the fan, 9.

In the case of a hard wood floor, it is desirable after removing the dust and dirt therefrom to polish the same by applying 45 wax or the like to the floor surface, and briskly rubbing the wax upon said surface, but a vacuum or suction sweeping apparatus is not adapted for such a polishing use for the reason that more or less free particles of wax would be drawn into the fan, tending to clog the same and more or less wax particles would be deposited within the 50 dust-bag, 22.

55 When it is desired to polish the floor with any substance, such as wax, which would tend to clog or injure the fan or the dust-bag, the cap, 12^a, can be removed and the closure-plate, 24, substituted therefor, thus closing the entrance to the fan-chamber and 60 eliminating the suctional action of the machine through the throat or passageway, 11.

65 This is readily accomplished by moving the slide, 15, back from beneath the tongue, on the cap, 12^a, withdrawing the cap from the machine and replacing the cap with the

closure-plate, 24, secured in position by engagement of the slide, 15, with the lug, 27, on the plate, as shown by solid lines in Figs. 1 and 2.

70 The closure-plate, 24, may be made in one piece or as shown in Fig. 3, it may be divided along its longitudinal middle.

When the closure-plate, 24, is made in one piece it is necessary when applying it to the machine to disengage the fan-belt, 18, from the fan-shaft pulley, 17, and the belt may be made sufficiently elastic to permit it to be stretched upon and off from said pulley.

75 In machines of the general type shown in the drawings, the brush-roll is rotatively mounted in a yoke, 29, pivoted at 30, upon the end walls of the brush-chamber, 12, and adapted to be swung about the axis of said pivotal connection from the brush operating position shown by solid lines in the drawings, to the position indicated by dotted lines in Fig. 4, in which dotted position, when the belt, 18, is disengaged from the fan-shaft pulley, 17, the trunnions of the brush-roll can be slid out from the slotted 90 bearings, 31, in the yoke, 29, to remove the brush-roll when desired.

80 Brush-rolls having peripheral surfaces of different form and materials may thus be mounted within the brush-chamber to adapt 85 the machine for the desired treatment of the floor surface.

85 By employing the divided plate, 24, shown in Fig. 3, removal of the fan-belt from the fan-shaft pulley, 17, is unnecessary, the two members of the plate being applied on opposite sides of the fan-shaft and the divided tongue secured by the slide, 15, in the same manner that the integral tongue is secured 90 as above described.

95 By the use of our invention, a suction cleaner or sweeper can by slight additional expense be rendered convertible into a floor waxer and polisher to take the place of floor 100 waxing and polishing machines, which are quite expensive and cumbersome.

105 What we claim as new and desire to secure by Letters Patent is—

110 1. The combination with a machine having a brush-chamber; a floor-engaging brush rotatively mounted in said brush-chamber; a fan-chamber provided with a bottom inlet-port connected with the brush-chamber by a throat; a fan-shaft extending from the fan-chamber through said port into said 115 throat; and a fan on the fan-shaft within the fan-chamber; of a removable closure for said port, said closure being provided with an opening to closely receive the extended portion of the fan-shaft.

120 2. The combination with a machine having a fan-chamber provided with a bottom inlet port; a brush-chamber; a passageway leading from the brush-chamber approximately to the port in the fan-chamber; a 125

brush rotatively mounted in the brush-chamber; a fan-shaft extending from the fan-chamber downwardly through said port; means for rotating the fan-shaft; and a belt connection between the lower end of the fan-shaft and said brush extending through said passageway; of a fan-shaft-receiving plate for closing said port and detachably connected with the fan-chamber.

In testimony whereof, we have hereunto ¹⁰ set our hands this 16th day of October, 1926.

ERNEST H. BLANCHARD.
DARWIN MOTT.
